UNITED STATES PATENT OFFICE.

ROBERT ARTHUR GOELLER, OF NEW YORK, N. Y.

LUG.

1,169,798.

Specification of Letters Patent.

Patented Feb. 1, 1916.

Application filed September 9, 1914. Serial No. 860,905.

To all whom it may concern:

Be it known that I, ROBERT A. GOELLER, a citizen of the United States, residing at New York, in the county of New York and

5 State of New York, have invented a new and useful Improvement in Lugs, of which the following is a specification.

This invention relates to a terminal connector for electric wires or cables known in 10 the electrical trade as a "lug." These lugs are usually given a high finish which is seriously marred by being subjected to the heat employed in soldering the cable thereto, and is also injuriously affected by the mechanical strain to which the lug is subjected 15 in placing the same in position. The ordinary workman is unable to repair the damage done by the heat and the tools employed, as he has neither the means nor the skill to 20 restore to the lug its original highly polished state.

This invention comprises a detachable cap for the lug which covers all of its exposed portion, and which receives the finish now 25 given to the lug itself, and which fitted into position after the soldering operation and other connections have been made, the same screws holding the lug to the bus-bar also 30 connecting the cap to the lug. By means of this invention it is also possible to form the polished or ornamented cap of a different metal from the lug itself.

In the drawings: Figure 1 is a perspective 35 view of the lug and cap, the cap being detached. Fig. 2, is a longitudinal sectional view through the lug with the cap in position.

Copies of this patent may be obtained for five cents each, by addressing the "Commissioner of Patents, Washington, D. C."

In these drawings 1 is the usual lug, which in this case is not given the usual exterior polish or finish, and 2 the base or 40 bar to which the lug is to be secured.

3 is a cap having the shape of the lug, open at one end and closed at the other, and adapted to fit over the lug, said cap receiving the finish usually given the lug, or being 45 ornamented in any desired manner. Openings 4 are formed in the lug for the passage of the securing means, generally screws, and 5 are openings in the cap which will align with the openings 4 of the lug. By means 50 of a cap of this kind the objects of my invention are fully accomplished.

What I claim is:

1. A terminal connector comprising a lug adapted to have a cable soldered thereto, 55 and a finished cap adapted to fit over said lug, and detachable therefrom, said cap being open at the cable attached end.

2. A lug of the kind described having openings for securing means to pass 60 through, a cap having an exterior finish or polish and having openings for securing means, said openings alining with those of the lug.

3. A two part lug, one part of said lug 65 having cable securing means and the other part having an exterior polish or finish, and common means for securing said parts in position.

ROBERT ARTHUR GOELLER.
